UNITED STATES PATENT OFFICE.

FREDERICK D. TAYLOR, OF CRANSTON, RHODE ISLAND.

TIDE MOTOR.

Application filed October 22, 1921. Serial No. 509,494.

To all whom it may concern:

Be it known that I, FREDERICK D. TAYLOR, a citizen of the United States, and resident of Cranston, in the county of Providence and 5 State of Rhode Island, have invented a new and Improved Tide Motor, of which the following is a full, clear, and exact description.

My invention relates to a tide motor and aims to provide certain new and useful improvements in connection with a device of 10 this character.

More particularly this invention is predicated to the provision of improvements upon my prior Patent #1047591 of December 17, 1912. It has been found in connection with the structure suggested in the patent referred to that certain difficulties have been experienced with reference to the mounting of the turbine members.

20 With this in mind my present invention aims to provide a tide motor, and the primary object of this invention is the mounting of the turbines by means of which any objections incident to this structure will be 25 avoided.

A further object of this invention is the provision of a device of the nature stated in which the general construction shall be improved and simplified in a manner herein- 30 after more fully brought out.

Still other objects of this invention will appear in the annexed specification taken in connection with the drawings which latter illustrate one practical embodiment of the 35 same and in which:

Figure 1 is a plan view of my improved type of tide motor.

Figure 2 is a sectional side view thereof and taken along the line 2—2 and in the 40 direction of the arrows indicated in Figure 1, and

Figure 3 is a transverse sectional end view taken along the line 3—3 and in the direction of the arrows also indicated in Figure 1.

Referring now more particularly to Figure 1 it will be seen that the reference numeral 5 indicates the channel which extends between the banks 6 and communicates with the tide water, this channel being dammed by means of the motor.

Primarily the motor is provided with a communication which includes a pair of spaced walls 7 extending across the channel 5, these walls being formed with openings 8 in communication with the channel 5. The

flow of water through these openings may be controlled by any suitable type of valve, but it will be noted that I preferably utilize gate valves 9 which conveniently provide 60 racks 10 adapted to be engaged by pinions 11, mounted upon a shaft 12 so that upon the latter being rotated, the valves 9 will be caused to close. Also in this connection it is 65 to be noted that the movement of these valves is perfectly synchronized by utilizing a main driving shaft 14 which transmits motion to a second shaft 15, the latter being coupled by means of gearing 16, to each of the shafts 12.

70 Thus upon the operator turning the shaft 14 associated with either wall 7 it will be obvious that he may adjust the flow of water through the openings 8 with that degree of nicety which is required to insure perfect 75 operation of the motor.

Attention is now invited to Figure 3 in which the motor is illustrated in detail, and it will be seen that this motor preferably includes a buoyant member such as a barge 17 80 capable of receiving a ballast 18. Secured to this member are conduits 19 constituting spill-ways and mounted adjacent the upper end of each of these conduits are turbine 85 wheels 20 secured to a shaft 21, the latter carrying any suitable type and size of gearing 22, which, meshing with a gear 23 will serve to operate the latter when the wheel 20 is revolved.

90 It will be obvious, reference being had to Figure 3, that the water may flow over the upper edge of one side of conduits 19 and through the wheels 20 associated therewith, thus operating the same subsequent to which water will pass through the bodies of the 95 conduits below the barge 17 and so through the openings 8 in the wall 7.

It will be seen that the barge 17 is formed with openings through which screw threaded shafts 24 extend, the said barge having 100 any desirable type of nut 25 secured to its body, which nuts are engaged one by each of the shafts 24 thus serving to adjust the barge upon the shafts being rotated.

A rotation of these shafts is accomplished 105 by utilizing gearing 26 of any preferred type the movement of the said shafts being synchronized by a drive 27. The motor 28 transmits motion to the gearing 26, and thus 110 it will be seen that an operation of the motor will result in a simultaneous rotation of all the shafts 24 and a corresponding move-

ment on the part of the barge 17 it being further noted that the said shafts 24 will act as guiding elements to the barge to help to guide it up and down as the tide rises and falls. The screw threaded shafts 24 pass through a frame 32 and have suitable bearings on the foundation of the wall 7 as shown more particularly in Figure 3. These shafts are used to adjust when necessary the level of the barge 17 and barges 31^a which are rigidly connected to the ends of barge 17.

The motor may be utilized to drive any suitable form of mechanism but in the embodiment illustrated the gearing 23 is secured to the shaft 29 which is mounted in bearings on the barges 31^a, the barges being movable in wells 33 formed by walls 34. The walls 34 are rectangular in shape and are connected to the opposite ends of the parallel walls 7.

Generators 30 are coupled to the ends of the shaft 29 whereby said generators are operated by the said shaft. The frame work 32 is located above the barge 17 and is supported in position at the upper ends of the vertical rods 35 which pass through the openings in the barge 17 and are rigidly connected with the foundation of the wall 7. These rods 35 not only support the frame 32 in elevated position but act as guides for the barge 17 and the barges 31^a during the vertical movement of said barges. It is to be noted that the frame 32 is stationary while the barges 17 and 31^a move relative to the stationary framework and are guided thereby so that the wheels 20 will get the full power from a thirty foot tide when the barges carry said wheels and the motors up or down upon the guide rods 35.

The conduit 19 being disposed longitudinally to and forming part of the barge 17 will be moved vertically with the barges and always have the same definite relation with the wheels 22 for controlling the flow of water outside of the wall 7 through the conduits 19 and either of the openings 8 at the bottom of said wall.

The operation of my device is as follows:

As shown more particularly in Figure 3, water passes over the outer edge of the conduit 19, through the wheels 20, operating said wheels, gear 23, shaft 29 and generators 30 operatively connected with the opposite ends of the shaft 29. The water passes downwardly through the conduit 19 below the barge 17 through the gates 8 in the wall 7 which is opposite to the wheels 20 which are operated by the flowing water, the water passing out as indicated by the arrow to the channel upon the other side of this wall.

The rising or falling of the water between the walls 7 tends to elevate or lower the barges 17 and 31^a as the case may be, but the barges are positively elevated or low-

ered by starting the motor 28, which revolves the threaded shaft 24 operating in the nuts 25 secured to the bottom of the barge 17. The elevation of the said barge properly positions one of the wheels 20 so that water can flow over the edges of the barges 31^a and drive said wheel 20.

Ebb tide causes rotation of the other wheel 20 and the gates 9 controlling ports 8 in the wall adjacent the last mentioned wheel are then closed through the manual operation of the shaft 14 by a wheel connected with said shaft.

The barges as has been stated are guided in their movement by the vertical rods 35 connected at their upper ends to the stationary frame 32 and at the other end to the foundation of the wall 7. The operation of the motor 28 merely serves the purpose of adjusting the level of the barge 17 and likewise the barges 31^a.

Cleats 40 are secured to the walls 34 of the wells 33 at points where the walls 7 are joined to the walls 34. These cleats extend over the water wheels 20, with the inner free ends of said cleats being perforated to receive the guide rods 35 and are for the purpose of bracing the upper end of said rods.

Thus all of the objects set forth in the preamble of this specification have been accomplished and it will further be understood that numerous modifications of structure might readily be resorted to without in the least departing from the scope of my claims; which are;

1. A tide motor including a pair of spaced walls, a movable mounting arranged between said walls, motor wheels carried by said mounting, openings formed in said mounting, screw threaded shafts extending through said openings, means for rotating said shafts, and means associated with said mounting and operatively connected with said shafts whereby rotation of the shafts adjustably positions the mounting.

2. A tide motor including a pair of spaced walls, a movable mounting arranged between said walls, motor wheels carried by said mounting, openings formed in said mounting, screw threaded shafts extending through said openings, means for rotating said shafts, means associated with said mounting and operatively connected with said shafts whereby rotation of the shafts adjustably positions the mounting, and means for synchronously rotating said shafts.

3. A tide motor mounting including a pair of spaced walls, a barge mounting movably positioned between said walls, said barge being formed with openings, nuts adjacent the lower ends of said openings, a plurality of screw threaded shafts extending through said openings and engaged by said

nuts, motors carried by said barge and means for rotating said shafts.

4. A tide motor including a pair of spaced walls, a frame extending between said walls, rods attached to said frame, a movable motor mounting also positioned between said walls, motors carried by said mounting, said mounting being formed with openings, said rods extending through said openings, and 10 acting as guides.

5. A tide motor including a pair of spaced walls, hollow piers adjacent the ends of said walls, said piers each providing a well, a frame extending between said walls, a 15 mounting slidably mounted upon said frame, motors carried by said mounting, extended portions forming a part of said frame and lying within said wells, elements adapted to be driven carried by said extended portions, 20 and means for connecting said motors with said elements.

6. A tide motor including a pair of spaced walls, extensions of said walls forming wells, a barge movable between said spaced walls, 25 barges connected to the ends of the first mentioned barge and movable in the extensions of said walls, conduits carried by the first mentioned barge, motors mounted at the upper ends of said conduits, and means for 30 guiding the barges in a vertical movement.

7. A tide motor including a pair of spaced

walls, extensions of said walls forming wells, a barge movable between said spaced walls, 35 barges connected to the ends of the first mentioned barge and movable in the extensions of said walls, conduits carried by the first mentioned barge, motors mounted at the upper ends of said conduits, means for guiding the barges in a vertical movement, and means for adjustably positioning the 40 barges.

8. A tide motor including a pair of spaced walls, barges mounted for vertical movement between said walls, motors carried by 45 said barges, and means for adjustably positioning the barges vertically.

9. A tide motor including a pair of spaced walls, barges mounted for vertical movement between said walls, motors carried by 50 said barges, means for adjustably positioning the barges vertically, and generators carried by said barges and operatively connected with the motor.

10. A tide motor including a pair of spaced walls, barges mounted for vertical 55 movement between said walls, motors carried by said barges, means for adjustably positioning the barges vertically, and conduits carried by said barges and located in alignment with the motors.

FREDERICK D. TAYLOR.
